[57] CLAIM

The ornamental design for a task light, substantially as shown and described.

DESCRIPTION

FIG. 1 is a top plan view of task light showing my new design;

FIG. 2 is a side elevational view thereof, the opposite side being a mirror image;

FIG. 3 is a front elevational view thereof;

FIG. 4 is a rear elevational view thereof;

FIG. 5 is a top plan view of a second embodiment of my new design;

FIG. 6 is a side elevational view thereof, the opposite side being a mirror image;

FIG. 7 is a rear elevational view thereof; and

FIG. 8 is a front elevational view thereof.
